TREATMENT OF HYDROCARBON OILS

Charles H. Angell, Chicago, Ill., assignor to Universal Oil Products Company, Chicago, Ill., a corporation of South Dakota

Application January 11, 1932, Serial No. 585,882

1 Claim. (Cl. 196—58)

This invention relates to the treatment of hydrocarbon oils and more specifically refers to an improved process and apparatus for separating light desirable components such as gasoline from crude petroleum, accompanied by pyrolytic conversion of heavier components of the crude.

It is the primary object of the present invention to provide an improved method and means for topping a crude oil and cracking the topped crude in a single operation utilizing heat recovered from the cracking system as a means of topping the crude oil and collecting, as the motor fuel product of the system, a blend of the gasoline naturally contained in the crude oil (straight-run gasoline) and products of similar boiling range resulting from cracking of heavier components of the crude.

The invention comprises, in one of its specific embodiments, subjecting a crude oil containing gasoline to vaporization within a low pressure zone of a cracking system under substantially non-cracking conditions by direct contact with heated conversion products of the system, separating the resulting vaporous and non-vaporous products, subjecting the vapors comprising vaporized portions of the crude and vaporous conversion products to fractionation whereby products of the desired motor fuel boiling range are separated from heavier products comprising insufficiently converted intermediate conversion products and portions of the crude which are first vaporized and subsequently condensed by fractionation to conversion conditions of elevated temperature and substantial super-atmospheric pressure in a heating element, introducing conversion products from the heating element into an enlarged reaction chamber where conversion, particularly of the vaporous products, is continued under super-atmospheric pressure, introducing both liquid and vaporous conversion products from the reaction zone to the aforementioned reduced pressure zone to which the crude oil is likewise introduced and returning a portion of the non-vaporous products comprising heavy nonvaporous components of the crude and residual liquid resulting from conversion to the stream of heated products entering the reaction chamber from the heating element.

Various modifications of the primary principles of the invention will be more specifically described in connection with the following description of the attached diagrammatic drawing. The drawing illustrates one specific form of apparatus suitable for the practice of the present invention. Attention is particularly directed to the

extreme simplicity of the apparatus, indicating the adaptability of the principles of the present invention to existing cracking processes.

Referring now to the drawing, heating element 1 is located within a furnace 2 of any suitable form from which heat required for conversion of the oil supplied to the heating element may be derived. The heated oil passes through line 3 and valve 4 into reaction chamber 5 which, like the heating element, is preferably maintained at a substantial super-atmospheric pressure and wherein products remaining vaporized are subjected to continued conversion for a predetermined time while relatively heavy non-vaporous products separate from the vapors and pass more rapidly to the lower portion of the chamber without substantial further conversion. Both liquid and vaporous products are withdrawn from chamber 5 through line 6 and valve 7, passing into vaporizing and topping chamber 8.

Crude oil or other raw oil charging stock for the system comprising a hydrocarbon oil containing a substantial proportion of gasoline or motor fuel fractions, may be supplied through line 9 and valve 10 to pump 11 from which it may be fed through line 12, valve 13, preheating coil 14, line 15 and either through line 16 and valve 17 into chamber 8 or through valve 18, in line 15, into the lower portion of chamber 5, or, if desired, partially in both directions. The raw oil supplied to chamber 5, as described, serves to dilute and cool the reaction products from this zone, passing through line 6 and valve 7 into chamber 8 thereby substantially preventing the formation of coke or carbonaceous material in this line. In either case, whether supplied directly to chamber 8 or into the lower portion of chamber 5, the charging stock is further heated by direct contact with the reaction products from chamber 5 and its substantial vaporization is effected in chamber 8. It will be understood that other well known methods of preheating the raw oil prior to its introduction into the topping chamber may be employed instead of or in conjunction with preheating coil 14 or, when desired, the raw oil may be supplied to the system without preheating. The preheater coil illustrated in the drawing is located within fractionator 19 and derives heat from the vapors in this zone. As examples of other means, not illustrated, by which the charging stock may be preheated, indirect heat exchange between the charging stock and the reflux condensate from the fractionator or between the charging stock

50

and vapors passing from vaporizing chamber 8 to fractionator 19 may be utilized.

Chamber 8 is preferably maintained at a substantially reduced pressure relative to that employed in chamber 5, which reduced pressure serves to assist vaporization of the non-vaporous oil introduced into this zone, also serving to assist cooling of the conversion products from chamber 5. Oil remaining unvaporized in chamber 8 is withdrawn through line 20 and may be removed, all or in part, from the system through line 21 and valve 22 to cooling and storage or to any desired further treatment. Preferably, however, a portion of the oil withdrawn from chamber 8 passes through valve 23, in line 20, to pump 24 from which it is fed through line 25 and valve 26 into the upper portion of chamber 5, entering this zone either through an independent line, not shown, or first comingling in line 3 with the heated oil from heating element 1 and passing therewith to chamber 5.

Vapors from chamber 8 pass through line 27 and valve 28 to fractionation in fractionator 19 by means of which the relatively heavy components of the vaporized portion of the charging stock and insufficiently converted components of the cracked vapors are condensed, collecting in the lower portion of the fractionator to be withdrawn therefrom through line 29 and valve 30 to pump 31 from which they are fed through line 32 and valve 33 to heating element 1 for conversion. Relatively light vapors, comprising desirable components topped from the charging stock in chamber 8 and the desirable cracked products are withdrawn from fractionator 19 through line 34 and valve 35, are subjected to condensation and cooling in condenser 36, distillate and uncondensable gas from which passes through line 37 and valve 38 to be collected in receiver 39. Uncondensable gas may be released from the receiver through line 40 and valve 41. Distillate may be withdrawn from receiver 39 through line 42 and valve 43.

In starting the operation of the process and in its initial stages, prior to the time when reflux condensate is produced in quantities sufficient to serve as the sole liquid heat carrying medium which is subjected to cracking in the heating element and thence utilized first to effect mild conversion of the unvaporized oil withdrawn from the low pressure chamber and subsequently to effect vaporization of the raw oil, some other oil must be substituted, all or in part, for the reflux condensate. The oil thus utilized as the heat carrying medium during the initial stages of the operation may be the regular raw oil charging stock for the system or, when desired, a lighter oil, more refractory to cracking, may be utilized for this purpose and in either case the supply of this material direct to the heating element is discontinued as soon as the production of reflux condensate is sufficient to maintain the desired regular operating conditions. Line 12', controlled by valve 13' is provided, connecting pump 11 with line 32 leading to heating element 1 by means of which pump 11 may supply the heat carrying medium to the heating element. This supply of raw oil direct to the heating element may be gradually diminished as reflux condensate from fractionator 19 is sup-

plied through line 29, valve 30, pump 31, line 32 and valve 33 to the heating element until the reflux condensate entirely replaces the other oil, following which the supply of crude to reaction chamber 5 and/or to reduced pressure chamber 8 may be started and gradually increased until equilibrium conditions are reached.

Conversion temperatures employed at the outlet of the heating element preferably range from 900 to 1050° F. and substantial super-atmospheric pressure ranging, for example, from 100 to 500 pounds, or more, per square inch is preferably employed in both the heating element and reaction chamber although pressure in the reaction chamber may be somewhat reduced, when desired, relative to that employed in the heating element. The vaporizing, fractionating, condensing and collecting portions of the system preferably utilize relatively low pressures ranging, for example, from 100 pounds per square inch down to substantially atmospheric pressure.

As a specific example of the operation of the process of the present invention, a 32° A. P. I. gravity mid-continent crude oil containing about 15 percent of straight-run gasoline having an octane number of approximately 50 is the charging stock supplied to the system. Reflux condensate from the fractionator of the system is subjected in the heating element to a temperature of approximately 940° F. under a super-atmospheric pressure of approximately 400 pounds per square inch. This pressure is substantially equalized in the reaction chamber of the system where, by the recirculation of the residual oil from the vaporizing chamber, the temperature is reduced to approximately 890° F. This operation may yield approximately 78 percent of motor fuel having an antiknock value approximately equivalent to a mixture of 75 percent iso-octane and 25 percent normal heptane. In addition about 15 percent of premium fuel oil is produced as the residual product of the system, the remaining 7 percent or thereabouts being chargeable principally to uncondensable gas.

I claim as my invention:

A combined topping and cracking process which comprises heating reflux condensate, formed as hereinafter set forth, to cracking temperature under pressure in a heating zone, discharging the heated reflux into the upper portion of an enlarged vertical reaction zone maintained under cracking conditions of temperature and pressure and passing both vapors and liquid downwardly through the reaction zone, removing the vapors and liquid as a mixture from the lower portion of the reaction zone and commingling crude oil containing natural gasoline therewith, discharging the commingled oils into a separating zone maintained under lower pressure than the reaction zone and separating the same therein into vapors and unvaporized oil, commingling at least a portion of said unvaporized oil with said heated reflux being discharged into the upper portion of the reaction zone, fractionating said vapors to condense heavier fractions thereof and supplying such condensed fractions to the heating zone as said reflux condensate, and finally condensing the fractionated vapors.

CHARLES H. ANGELL.
